UNITED STATES PATENT OFFICE.

SOLOMON S. MECAY, OF KILBOURNE, OHIO, ASSIGNOR TO SPENCER MECAY, OF SAME PLACE.

IMPROVEMENT IN ROTARY ENGINES.

Specification forming part of Letters Patent No. 37,841, dated March 3, 1863.

To all whom it may concern:

Be it known that I, SOLOMON S. MECAY, resident of Kilbourne, in the county of Delaware and State of Ohio, have invented and made certain new and useful Improvements in Rotary Steam-Engines; and I do hereby declare that the following is a full, clear, and exact description of the same, reference being had to the accompanying drawings, making a part of this specification, in which—

Figure 1 is a perspective view of the rotating steam chest or drum with one of the circular heads detached. Fig. 2 is a full end view showing one of the heads of the drum detached, exposing the interior construction or arrangement of parts. Fig. 3 is a side view of the periphery of the drum with the shaft or axle thereof.

My improvements relate more especially to the construction and arrangement of the drum or propelling-cylinder, also to the steam education channels and exhaust-outlets of rotary engines; and the nature of said improvements consists in so increasing the internal area of the steam-drum as to produce a greater capacity for an accumulating volume of steam, and, furthermore, so forming and arranging the education-channels and exhaust-outlets in such a manner, remote and disconnected from the ports, as to receive a greater pressure thereagainst by compression, yet diminishing the surface of friction, resulting in an increased energy or power of the engine.

The construction of my improvements is shown in Figs. 1, 2, 3, the letters of reference A A A marking the shaft or axle, which is tubular or hollow, from A' up to a short distance beyond the ports or steam-vents B B, the other portion of the axle being solid. Said shaft or axle is affixed permanently through the heads or circular plates C C, which are attached permanently to the four segmental rims, D D D D, which have one of their ends turned over or bent backwardly in form of a hook, as at E E E E, Figs. 1, 2; and when arranged in their relative position to the head-plates C C their hooked ends are situated beneath each other's curved end. The circle which each segment would describe if continued would be eccentric to the circle described by the circumference of the drum C C, Fig. 2, and thus situated the hooked

ends E E E E of the rims D D D D tend said ends inwardly toward the center and axle of the drum, and thereby admit of suitable recesses or short education-channels, F F F F, terminating in exhaust issues or outlets G G G G, Figs. 1, 2. By this form of construction the exhaust issues or outlets can be enlarged to any desired capacity, so as to pass off a greater column of the accumulating volume of steam in the chamber I I I I, thereby affording an increased reactive power.

In Fig. 3 my rotary engine is represented in a horizontal position on its shaft or axle A A', which shaft or axle may be mounted and arranged in suitable bearings and standards as may be required for its working, the induction-pipe employed connecting with any required steam-generating apparatus, the shaft A A A' being provided with a band-pulley, H, or, if desired, a crank attachment may be employed to transmit motion to machinery as required.

To understand fully the advantages of my improvements by an examination of the various well-known rotary engines and other motors in use it will be found that they are generally formed of radial tubular channels, or of curved hollow education-passages, commencing immediately at the junction of the port-inlets, and therefrom continuing outwardly direct toward the circumference of the drum or cylinder of the engine. In all such forms of construction the volume of steam passing through the ports of the induction-pipe is separated into several small distinct volumes or currents, which act only within and on the surfaces of said radial tubular channels. Thus the power of steam will diminish in proportion to the extended surfaces of friction presented; and, furthermore, as the steam passes so directly out from the ports through the exits or exhaust-outlets, no accumulating volume of steam can be afforded. But after my plan of constructing rotary motors it will be perceived that, owing to the increased capacity or internal area of surfaces, afforded by dispensing with the radial channels, a very great diminution of friction and its counteracting resistance are overcome, and, consequently, a very greatly increased volume of power is immediately brought into action, and, as the volume of steam entering through

the ports B B rushes off toward the segmental rims D D D D, that portion of the steam passing into the channels F F F F is greatly compressed, and must necessarily force out through the issues or exhaust-outlets G G G G with very great power, from which ensues increased centrifugal action, operating on the whole circumference of the drum or cylinder, and, as it were, the inclosed volume of accumulating steam in the chamber I I I I converting itself into an encompassing continuous leverage power, the axis of the shaft A A being the fulcrum of power, and thus, according to the ratio of the continuously-supplying volume of steam over the quantity discharging, so is the ratio of outwardly-acting pressure. Hence, it is maintained that by diminishing the surfaces of friction and by concentrating the pressure of the accumulating volume of steam upon the small outgoing columns through the channels F F F F there must necessarily be developed a greatly-accelerated power from a given amount of steam than if the same amount of steam were applied by the other mentioned modes of construction.

The operation of my improvements is brought about by introducing through the induction-pipe or hollow shaft A the necessary flow of steam, which, forcing through the ports B B, will fill the chamber or area I I I I of the drum C C C C, Figs. 1 and 2, and therein accumulating in volume will rush toward the circumference of the drum, accumulating within the short channels or recesses F F F F, and there, becoming very greatly compressed, will force outwardly through the issues or exhaust-outlets G G G G in a tangential direction relative to the circumference of the drum and the line of motion thereof. Thus it will be readily perceived that the short channels or recesses F F F F present but a very limited surface of friction, whereas, if the long continuous radial or curved ejection-channels were employed and the incoming flow of steam divided into several small columns, and had to pass over surfaces of resistance continued from the ports toward the outlets in the direction of the arrows, the amount of friction that would have to be overcome would be nearly four times as great in

each long channel as it would be in the short channels; and this fact can very readily be demonstrated by a simple practical calculation, thereby fully proving the advantages and utility of my improvements over all others referred to.

The flow of steam and the force thereof may be readily regulated by a sliding or revolving sleeve situated within the hollow shaft, or by any other suitable valve arrangement, and, though not represented in the accompanying drawings, by making the drum or propelling-cylinder C C C C D D, Fig. 3, double or with two sets of segmental rims, and reversing the arrangement of one set by turning the convex or hooked ends E E E E in opposite directions, a reversing motion may be produced, thus admitting of applying my rotary engine to locomotive propulsion as well as to the driving of local machinery.

Deeming the foregoing description of my improvements sufficiently full and clear to enable others to construct and use them, and having clearly set forth and explained the advantages thereof over other rotary engines having hollow, radial, and extended curved arms or ejection-channels, and being well aware that such last-named forms of construction have long been known and used, therefore such forms of construction I do not claim; but

What I do claim as of my own invention, and desire to have secured by Letters Patent of the United States, is—

Constructing the drum or propelling-cylinder of a rotary steam or other motor with segmental rims D D D D having hooked or bent ends E E E E, so combined and arranged together as to form short compressing-channels F F F F and exhaust-outlets G G G G, disconnected and remote from the ports B B, and whereby is acquired an enlarged area of capacity and an accumulating-chamber, I I I I, thereby affording an increased volume of steam and also avoiding friction, substantially as set forth, shown, and described.
